CANDELABRUM OR SIMILAR ARTICLE

Gilbert Josephson, White Plains, N. Y.

Application July 27, 1954, Serial No. 31,631

Term of patent 14 years

(Cl. D48—2)

FIG. 1

To all whom it may concern:

Be it known that I, Gilbert Josephson, a citizen of the United States of America, residing at White Plains, county of Westchester, and State of New York, have invented a new, original, and ornamental Design for a Candelabrum or Similar Article, of which the following is a specification, reference being had to the accompanying drawing, forming part thereof.

Fig. 1 is a plan view of a candelabrum showing my new design; and

Fig. 2 is a front elevational view thereof, the side and rear elevational views corresponding in all respects to the front elevational view.

I claim:

The ornamental design for a candelabrum or similar article, substantially as shown and described.
